EDGE BINDING AND METHOD OF APPLYING SAME

Application filed April 13, 1928. Serial No. 269,850.

This invention relates to an edge binding for sheet material and to a method of making and applying the binding to finish the edges of sheet material and although capable of general use is more particularly designed for use in the shoe manufacturing industry.

In the manufacture of shoes, it has heretofore been customary to finish the edges of certain parts of the shoes, such as uppers, vamps, straps, and similar parts, with what has been commonly called French cord binding. This is accomplished by placing the binding flat on the right face of the shoe part and then stitching the two together by a row of stitching close to their edges. The binding is then turned in a reverse direction around the edge of the shoe part concealing the stitching and the free edge of the binding is cemented to the wrong side of the shoe part. The reverse turning of the binding over its stitched edge and around the edge of the shoe part presents an appearance from the right side of the shoe part of a cord binding, hence the name. In many cases, it has been customary to reenforce the shoe part on its wrong side and adjacent its edge with a strip or stay of suitable reenforcing material and generally this is done before the binding is turned over upon the wrong side of the shoe part so that the binding will ultimately cover the reenforcing strip. It may, however, be done in the reverse order. The application of the lining to the shoe part conceals the turned over edge of the binding and the stay. This work, however, involves a number of separate operations performed by different operators and necessitates the passing of the shoe from one to the other through a number of steps, all of which consume time and labor and involve expense.

The principal object of our invention is the provision of a binding which is adapted to stay or reenforce the edge of the shoe part to which it is applied and to this end the binding includes a reenforcing strip secured to one face thereof in any suitable manner, the reenforcing strip being of a lesser width than the binding so that when the binding is applied the reenforcing strip is properly positioned on the shoe part.

Another object of the invention is the provision of a binding made in strip form which can be manufactured at a low cost.

A further object is the provision of a method for binding the edge of sheet material which will eliminate some of the steps now required, which will obtain a better result and better finished edges and which greatly reduces the expense of the binding operation and permits the work to go through more rapidly.

Other objects of the invention will be more specifically set forth and described hereinafter.

Referring to the drawings illustrating our invention, Figure 1 is a sectional view of a shoe part in sheet form having attached to one edge thereof by stitching a binding constructed in accordance with our invention, the binding being shown after it has been stitched to the shoe part and before it has been turned around the edge; Fig. 2 is a similar view of a binding turned in a reverse direction around the edge of the shoe part and secured to the wrong face of the shoe part; Fig. 3 is a cross-sectional view of a binding strip constructed in accordance with our invention and Fig. 4 is a view in perspective of a portion of a shoe upper provided with an elongated strap, said shoe part being shown as bound with a binding made in accordance with our invention, one end of the binding strip being opened up to illustrate its application to the shoe part.

Referring to the drawings, 10 designates a binding strip of any suitable material which is preferably provided with at least one selvaged edge 12 to prevent the stitches pulling out when it is stitched at that edge to a shoe part. The other edge 14 may or may not be selvaged as desired. To one face of the binding strip is secured a strip 16 of suitable reenforcing material of lesser width than the width of the binding strip, the reenforcing strip being positioned adjacent the unselvaged edge of the binding. The reenforcing strip 16 may be secured to the binding strip by cement or other adhesive (as shown in Fig. 3) or by stitching or by any other means or it may be formed in the binding 100

in the weaving process as an integral part thereof. The binding is made in a continuous form as a tape or ribbon rolled or wound on a board and is cut off in suitable lengths for use.

- 5 Preferably, the reenforced portion of the binding is of such width in relation to the width of the binding that when the binding is used, the reenforced portion lies entirely 10 on the wrong side of the shoe part and does not extend over the edge thereof, the edge being covered by the unreenforced portion of the binding. Thereby, a neat, even and tight fold around the edge of the shoe part may 15 be attained.

In carrying out our method in French cord binding, the binding 10 is first positioned on the right side of the shoe part 20 with its selvaged edge 12 in register with the 20 edge 22 of the shoe part and secured thereto by a row of stitching 24 adjacent the edges as shown in Figure 1. The binding after being stitched is then turned in a reverse direction around the edge of the shoe part to be 25 bound and its free edge 14 is preferably cemented to the wrong side of the shoe part as shown in Fig. 2. In positioning the binding in relation to the shoe part preparatory to stitching it thereto, it may be so placed 30 that the reenforcing tape will lie finally as shown in Fig. 2 between the free edge of the binding and the wrong face of the shoe or will lie outside of the binding with the latter between the former and the reenforcing 35 strip.

Certain steps of our method such as stitching the binding to the shoe part and turning it around the edge to be bound may be carried out by the use of suitable sewing and 40 folding machines respectively or the entire method may be carried out by hand if desired.

It will be observed that by the use of our method the various steps now required in 45 binding the edges of shoe parts have been reduced to a minimum and certain steps involving movement of shoe parts back and forth from one operator to another have been eliminated, thereby effecting an economy of 50 manufacture and facilitating the progress of the work through the factory. In addition the work is improved in character for the reason that when the reenforcing strip or stay is made an integral part of the binding, 55 it is accurately located in relation to the edge to be reenforced thereby bringing about work which is uniform, accurately reenforced and neat. Our method further eliminates the cementing process required when the re- 60 enforced strip or stay is cemented to the shoe part independently of the application of the binding, which, of course, is a desired advantage because any reduction in cementing in a shoe factory is of marked benefit. This is 65 especially emphasized in binding shoe parts

of the character shown in Fig. 4 of the drawings having narrow elongated straps which are especially difficult to handle in performing binding operations.

Although we have described our invention 70 for purposes of illustration only in relation to its application to shoe parts, it is to be understood that it is equally applicable for binding a sheet material used in other industries. Furthermore, the invention is not to be restricted to what is termed French cord binding only since it may be used with other forms of binding where it is desirable to have the edge reenforced. 75

What we claim is:

1. A woven binding strip for binding the edge of sheet material having secured to one face a strip of tape reenforcing material of lesser width than the width of said binding strip. 80

2. A woven binding strip for binding the edge of sheet material, having secured to one face thereof a strip of reenforcing material of lesser width than the width of said binding strip, one edge of said reenforcing strip being substantially in register with one edge of said binding strip. 85 90

3. An elongated woven binding strip for binding the edge of sheet material, provided with a selvaged edge and having a strip of reenforcing material secured to one face thereof with one edge in register with one edge of said binding strip, said reenforcing strip being in width approximately one half of the width of said binding strip. 95 100

4. A woven binding strip selvaged on one edge for binding the edge of sheet material and having cemented to one face thereof a strip of reenforcing tape of lesser width than the width of said binding strip; one edge of said tape being in register with the selvaged edge of said binding strip. 105

5. The herein described method of binding sheet material consisting in providing an elongated binding strip having one edge selvaged, cementing to one face of said binding strip a strip of reenforcing tape with its edge adjacent with the unselvaged edge of said binding strip, said reenforcing strip being of lesser width than the width of said binding strip, then stitching said binding strip along its selvaged edge to the right face of the sheet material to be bound at the edge thereof, then turning said binding in reverse direction around the edge of said sheet material and securing said reenforced portion of said binding to the reverse side of said sheet material. 110 115 120

6. The herein described method of simultaneously binding and reinforcing the edge of sheet material consisting in securing to one face of a woven binding strip adjacent one edge thereof a strip of reinforcing tape of lesser width than the width of said binding strip, then stitching said binding strip along its unreinforced edge to the right face of the 125 130

sheet material to be bound at the edge thereof, then turning said binding in a reverse direction around the edge of said sheet material and securing the reinforced portion of said binding to the reverse side of said sheet material.

7. A woven binding strip selvaged on one edge for binding the edge of sheet material and having that portion adjacent the other edge of approximately double thickness in order that when said last mentioned edge is turned over upon the reverse side of said sheet material, the said double thickness will serve as a reinforcement for said edge.

15 In witness whereof, we have hereunto set our hands this eleventh day of April, 1928.

ERNEST J. ORDWAY.
A. EVERETT CUSHING.
